Filed July 6, 1965, Ser. No. 469,372
9 Claims. (Cl. 308—4)

ABSTRACT OF THE DISCLOSURE

A rod guide for a sucker rod and comprising a pair of substantially identical half-sections adapted to be secured in abutting relationship around the outer periphery of the rod, threaded members extending transversely between the half-sections for securing the half-sections around the rod, keeper members provided in the first half section for retaining the threaded members therein against accidental loss prior to threaded engagement with the threaded members of the other half-section, the threaded members in the second half-section being wedged securely therein against rotation and for precluding loss thereof from the second half-section prior to securing the half-sections around the rod.

This invention relates to improvements in rod guides for sucker rods in pumping oil wells and more particularly, but not by way of limitation, to a rod guide particularly designed and constructed for simplicity and efficiency of installation on the rod.

As is well known, the sucker rods in pumping oil wells normally extend longitudinally through the well bore or well tubing and are reciprocated therein during the pumping operation. Since most well bores are not straight, and many are purposefully drilled at an angle, the rods frequently wear against or engage the walls of the tubing during the reciprocation thereof, which creates detrimental wear on the rods. In addition, most of the rods are constructed of metal, and are usually subject to electrolytic action resulting from the electrical forces normally present underground, which further damages the rods and requires replacement thereof. It is usually necessary to pull the rods from the well bore in order to replace or repair the damaged portion thereof. This is expensive and time consuming, particularly in deep wells wherein the rod may be extremely long.

In an effort to reduce the wear of the rods against the sidewalls of the well tubing, many rod guide devices have been developed for installation around the outer periphery of the rod and spaced longitudinally therealong. These guides are disposed around the outer periphery of the rods and spaced therealong for protecting the rods against engagement with the well tubing. Of course, it is desirable to install the guides around the rod in a lateral direction rather than a longitudinal direction due to the length of the rods. This has created a problem in that it is frequently difficult to secure the guides around the rod in a manner for precluding slippage of the guides along the rod. In addition, bolts, or the like, which are often utilized for securing the guides on the rod, frequently loosen

2

and fall downwardly in the well bore and damage the pumping equipment. Furthermore, most of these guide devices are constructed from wood or rubber materials, in order to reduce the corrosion action due to the well fluids, and consequently are often not durable in construction.

The present invention contemplates a novel rod guide particularly designed and constructed for ease of installation around a sucker rod, and to substantially eliminate the loss of the securing members therefrom. In addition, the novel rod guide is constructed from a suitable plastic material, such as nylon, which is corrosion resistant, and has insulating properties for protection of the rod from electrolytic action. The rod guide comprises two half-sections adapted to be secured in abutting engagement around the outer periphery of the rod. Each half-section is provided with a plurality of transversely extending bores adapted for alignment with the respective bores of the other half section whereby threaded members and complementary lock nuts may be utilized for securing the two half-sections around the rod. The half-sections are particularly constructed for insertion of all the threaded members from the same side of the guide, thus greatly reducing installation time. In addition, the threaded members and lock nuts are disposed within the respective half-sections prior to shipping thereof, thus reducing the necessity of inserting the bolts and nuts at the installation site. The nuts are inserted in a manner for becoming securely positioned in one half-section and keeper means is provided integral with the other half-section for precluding accidental loss of the bolts therefrom prior to disposition of the guide around the rod. In addition, the bolt and nut means utilized for securing the half-sections around the rod are of the self-locking type to eliminate accidental loosening of the bolts and loss from the guide member subsequent to installation thereof around the rod. The novel rod guide is simple and efficient in operation and economical and durable in construction.

It is an important object of this invention to provide a novel rod guide particularly designed and constructed for facilitating the installation thereof on a sucker rod, or the like.

It is another object of this invention to provide a novel rod guide wherein the threaded securing members may be inserted from the same side of the guide for reducing installation time.

Still another object of this invention is to provide a novel rod guide wherein the securing members may be inserted therein prior to shipping thereof for further reducing installation time.

A further object of this invention is to provide a novel rod guide wherein means is provided for precluding accidental loss of the securing members therefrom prior to installation of the guide around the rod.

A still further object of this invention is to provide a novel rod guide wherein the securing members are locked in the engaged position subsequent to installation of the guide around the rod for substantially precluding accidental loss of the securing members.

Other and further objects and advantageous features of the present invention will hereinafter more fully appear in connection with a detailed description of the drawings in which:

FIGURE 1 is a side elevational view of a half-section of a rod guide embodying the invention disposed on a rod, with the rod being depicted in dotted lines for purposes of illustration.

FIGURE 2 is a side elevational view of a rod guide embodying the invention installed around a rod, with a portion thereof depicted in section, said section being taken in line 2—2 of FIGURE 3.

FIGURE 3 is an end elevational view of a rod guide embodying the invention disposed around a rod, with the rod depicted in section.

FIGURE 4 is an enlarged broken sectional view of a portion of one rod guide half-section particularly illustrating the keeper member.

FIGURE 5 is a side elevational view of a stud member and complementary lock nut as may be utilized in the invention, with the nut being depicted in section for purposes of illustration.

Referring to the drawings in detail, reference character 10 generally indicates a substantially cylindrical rod guide comprising a pair of substantially identical half-sections 12 and 14 adapted to be secured around the outer periphery of a reciprocal rod 16. The guide 10 is preferably molded or otherwise constructed from a suitable plastic material having corrosion resistant qualities and insulating qualities, such as molydisulphide nylon. The half-section 12 is substantially semi-cylindrical and is provided with a centrally disposed semi-circular groove or recess 18 extending longitudinally therealong adapted for engagement against the outer periphery of the rod 16. The central portion of the recess 18 is enlarged or relieved at 20 in order to assure that the spaced portions of the recess 18 will efficiently engage the outer periphery of the rod. Thus, any unevenness in either the outer periphery of the rod 16, or the recess 18 will be compensated for, whereby the half-section 12 may be snugly disposed adjacent the rod 16.

The half section 12 is further provided with a plurality of spaced bores 22, 22a, 22b, and 22c extending transversely therethrough. Each bore 22, 22a, 22b and 22c is substantially identical, and as shown in FIGURE 2, the bore 22 is provided with an enlarged portion 24 to provide an annular shoulder 26 for receiving a suitable locking member or insert 28 thereagainst. The outer periphery of the lock nut or insert 28 is fluted or provided with radially extending circumferentially spaced pointed or sharp members which bite into the inner periphery of the bore portion 24 as the insert 28 is passed into position therein. This securely fastens the insert 28 within the half-section 12 and precludes rotation of the nut 28 with respect thereto. Of course, each bore 22, 22a, 22b, and 22c are similarly provided with enlarged portions for receiving a lock nut or insert member therein.

A plurality of circumferentially spaced longitudinally extending recesses or flutes 32 are provided around the outer periphery of the half-section 12. The flutes 32 provide fluid passageways for the well fluids, both liquids and gases, during reciprocation of the bore 16. This facilitates the passage of the well fluids between the guide 10 and well tubing (not shown).

As hereinbefore set forth, the half-section 14 is substantially identical to the half-section 12 and is provided with a centrally disposed bore 34 similar to the bore 18 extending longitudinally therealong for engagement with the outer periphery of the rod 16. The bore 34 is also provided with a centrally disposed enlarged or relieved portion (not shown) similar to the portion 20 and for the same purpose. In addition, a plurality of spaced bores similar to the bores 22, 22a, 22b, and 22c extend transversely through the half-section. However, only three of the transversely extending bores 36, 36a, and 36b of the half-section 14 are depicted in the drawings. Each of the bores 36, 36a, and 36b are substantially identical and as depicted in FIGURE 2, the bore 36 is provided with an enlarged portion 38 providing an annular shoulder 40 for

receiving the head 42 of a threaded bolt 44, or the like, thereagainst. A relatively thin inwardly directed annular lip of feeler member 46 is provided in the proximity of the exposed end of the bore 36. The feeler 46 is of a thickness of approximately .010 inch and will flex sufficiently upon the insertion of the threaded member 44 into the bore 36 for engaging the threaded portion thereof for holding the threaded stud within the bore 36 prior to shipping of the guide 10 for precluding accidental loss of the threaded member 44 therefrom.

A plurality of circumferentially spaced longitudinally extending recesses or flutes 48, similar to the flutes 32, are provided on the outer periphery of the half-section 14. The flutes 48 provide additional passageways for flow or movement of the well fluids between the guide 10 and the well tubing.

The transversely extending bores of the half-section 14 are disposed in substantial alignment with the transversely extending bores of the half-section 12 when the two half-sections are disposed in abutting relationship around the outer periphery of the rod 16. The threaded members 44 may then be threadedly secured to the lock nuts 28 in order to retain the guide 10 in position around the rod 16.

The studs 44 and inserts 28 are of any suitable self-locking type. For example, the stud 44 may be provided with a longitudinally extending nylon insert (not shown) disposed in the threaded shank thereof and extending radially beyond the outer periphery of the threads. Thus, when the stud 44 is threadedly engaged with the insert 28, the nylon material will flow into the space between the threads for locking the elements together. Alternately, a portion of the threads of each threaded member 44 may be provided with a relatively thin coating of one component of a suitable epoxy glue, such as is well known and in wide spread use today and as shown at 45 in FIGURE 5. The internal threads (not shown) of each lock nut 28 are preferably provided with a similar coating of the second component of the epoxy glue as shown at 29 in FIGURE 5. The use of such an epoxy type cement or glue is disclosed in the Jay D. Anthony Patent No. 3,061,455, issued Oct. 30, 1962, and entitled "Self-Locking Threaded Fastener." When the threaded members 44 are threadedly engaged with the respective lock nuts 28, the coatings of the complementary threads thereof will react chemically due to the friction engagement for securely cementing or glueing the threaded members 44 within the lock nuts 28. This substantially precludes any accidental loss of either the threaded members 44 or lock nuts 28 from the respective bores 36 and 22. Of course, any suitable self-locking means may be utilized for the studs 44 and nuts 28.

Of course, the heads 42 of the threaded members 44 may be provided with sockets (not shown) for receiving a suitable socket wrench (not shown) therein in order to facilitate the threaded members 44 with the respective nuts 28. As hereinbefore set forth, the outer periphery of the nuts 28 bites into the periphery of the bores 22 for anchoring the nuts 28 therein, thus facilitating the threading of the members 44 in the nuts 26.

By way of summary, the rod guide 10 comprises the two semi-cylindrical half-sections 12 and 14 which may have the locking nuts 28 disposed within the bores 22 of one half-section and the threaded members 44 loosely disposed within the bores 36 of the other half-section prior to shipment of the guide 10 to the field installation site. The biting engagement of the nuts 28 with their respective bores 22 retain the nuts 28 in the bores 22, and the keeper members 46 retain the threaded members 44 in the respective bores 36 during shipment and prior to installation of the half-sections 12 and 14 around the rod 16. The half-sections 12 and 14 may be disposed in abutting relationship around the outer periphery of the rod 16 whereby the respective bores 22 and 36 are in substantial alignment. The threaded members 44 may then be tightly engaged with the respective lock nuts 28 for secur-

ing the half-section 12 and 14 around the rod. In addition, since the members 44 and 28 are of a self-locking type the nuts and studs are locked in the threadedly engaged position therebetween for substantially precluding loosening thereof or accidental loss thereof subsequent to disposition of the rod guide 10 around the rod 16. The abrasion and corrosion resistant qualities of the nylon in combination with the insulating qualities thereof efficiently protects the rod 16 from wear due to engagement with the well tubing and from electrolytic action.

Of course, substantially any number of the guides 10 may be secured to the rod 16 and spaced therealong as desired. It is usually preferable to locate the guide 10 in the proximity of the tubing couplings (not shown) and in the center of a length of rod where there may be buckling or whipping, but there is no limitation for the positioning or spacing of the guides. It is to be noted that all of the threaded members 44 are installed from the same side of the guide 10, thus greatly reducing the time for installation of the guide around the rod 10. In addition, the threaded members 44 and locking nuts 28 are constructed from a suitable corrosion resistant material, such as stainless steel, or the like. Thus, the useful and efficient life of the rod guide 10 is greatly prolonged.

From the foregoing it will be apparent that the present invention provides a novel rod guide for a sucker rod which is particularly designed and constructed for speed and ease of installation on the outer periphery of the rod. In addition, the rod guide is provided with means for securely retaining the guide in position around the outer periphery of the rod, and for substantially precluding accidental loss of the securing members during reciprocation of the rod during the pumping operations. The novel guide substantially reduces wear and electrolytic damage to the rod for prolonging the useful life thereof, thus reducing the expense of operation of the well. The novel rod guide is simple and efficient in operation and economical and durable in construction.

Changes may be made in the combination and arrangement of parts as heretofore set forth in the specification and shown in the drawings, it being understood that any modification in the precise embodiment of the invention may be made within the scope of the following claims, without departing from the spirit of the invention.

What is claimed is:

1. A rod guide for a sucker rod and comprising a pair of substantially identical half-sections adapted to be secured in abutting relationship around the outer periphery of the rod, each of said half-sections being provided with a plurality of spaced transversely extending bores in alignment with complementary bores of the other half-section, threaded means disposed in the bores of each half-section prior to installation thereof around the rod, means precluding accidental loss of the threaded means from the respective bores prior to installation of the half-sections around the rod, said threaded means in each half-section engageable with the threaded means in the other half-section for tightly securing the half-sections in position around the rod, and means cooperating with the threaded means for locking the threaded means subsequent to the installation of the half-sections around the rod.

2. A rod guide for a sucker rod and as set forth in claim 1 wherein the means for precluding accidental loss of the threaded means from the respective bores comprises an integral inwardly directed annular keeper member provided in the bores of one half-section and engageable with the respective threaded means disposed therein, and fluted means provided on the outer periphery the portion of the threaded means disposed in the bores of the other half-section with said fluted means being engageable with the inner periphery of the respective bore.

3. A rod guide for a sucker rod and as set forth in claim 1 wherein the means for locking the threaded

means subsequent to the installation of the half-sections around the rod comprises an epoxy cement activated by the threaded engagement of the threaded means for cementing the threaded means in a locking position.

5. A rod guide for a sucker rod and as set forth in claim 1 wherein the threaded means comprises a plurality of locking nuts disposed in each of the bores of one half-section, and threaded members loosely disposed in each of the bores of the other half-section for threaded engagement with the respective locking nuts upon disposition of the half-sections around the outer periphery of the rod.

10 5. A rod guide for a sucker rod and comprising a pair of substantially semi-cylindrical half-sections, each of said half-sections being provided with a centrally disposed longitudinally extending semi-circular recess for engagement with the outer periphery of the rod, a plurality of spaced transversely extending bores provided in the first half-section, a plurality of spaced transversely extending bores provided in the second half-section and disposed in substantial alignment with the bores provided in the first half-section, locking nut means disposed within the bores of the first half-section, threaded means loosely disposed within the bores of the second half-section, means integral with the second half-section for precluding accidental loss of the threaded means from the respective bores, means cooperating between the locking nut means and respective bores for resisting rotation of the locking nut means within said bores, said threaded means adapted for threaded engagement with the locking nut means for tightly securing the two half-sections in position around the outer periphery of the rod, and means cooperating between the threaded means and locking nut means for locking the nut and threaded means together for substantially precluding accidental loss thereof subsequent to the threaded engagement therebetween.

25 6. A rod guide for a sucker rod and as set forth in claim 5 wherein the means for locking the threaded means and nut in the threaded engagement therebetween comprises an epoxy cement wherein one component thereof is initially provided on the threaded means and the second component thereof is initially provided on the locking nut means, said epoxy components being activated by the threaded engagement for cementing the threaded means within the locking nut means.

30 7. A rod guide for a sucker rod comprising a pair of substantially semi-cylindrical half-sections adapted to be disposed around the outer periphery of the rod in abutting relationship, each of said half-sections provided with a centrally disposed semi-circular recess extending longitudinally therealong for engagement with the outer periphery of the rod, each of said recesses being provided with an enlarged portion for facilitating disposition of the recesses adjacent the rod, a plurality of spaced bores provided in each half-section and extending transversely therethrough in substantial alignment with the bores of the other half-section, each of said bores being provided with an enlarged portion to provide an annular shoulder therein, locking nut means disposed in each bore of one half-section for engagement with the respective annular shoulder, threaded stud means loosely disposed in the bores of the second half-section, for engagement with the respective annular shoulder, keeper means provided for each bore of the said second half-section to preclude accidental loss of the threaded stud means therefrom, said locking nut means provided with a fluted outer periphery for gripping the periphery of the enlarged bore portion for resisting rotation therein, and said threaded stud means engageable with said locking nut means in the abutting position of the half-sections for securing the half-sections around the periphery of the rod.

35 8. A rod guide for a sucker rod and as set forth in claim 7 and including means cooperating between the

locking nut means and threaded stud means for precluding accidental loosening thereof subsequent to the threaded engagement therebetween.

9. A rod guide for a sucker rod as set forth in claim 7 and including cement means cooperating between the locking nut means and threaded stud means for precluding accidental loosening thereof subsequent to the threaded engagement therebetween, said cement means comprising two components wherein one component is provided on the outer periphery of the last portion of the threaded stud means and the second component is provided on the inner periphery of the locking nut means, said two components being activated upon the threaded engagement between the locking nut means and threaded stud means for cementing thereof in the threaded engagement therebetween.
